UNITED STATES PATENT OFFICE.

CHARLES H. BESLY, OF CHICAGO, ILLINOIS.

DESIGN FOR A LETTER-OPENER.

SPECIFICATION forming part of Design No. 24,941, dated December 3, 1895.

Application filed October 14, 1895. Serial No. 565,695. Term of patent 14 years.

To all whom it may concern:

Be it known that I, CHARLES H. BESLY, a citizen of the United States, residing at Chicago, in the county of Cook and State of Illinois, have invented a certain Design for Letter-Openers, of which the following is a specification.

My design relates to letter-openers, and is illustrated in the accompanying drawing, which shows a plan view of the letter-opener.

The letter-opener consists of the narrow pointed blade A, the handle B, and the enlarged part C. This enlarged part is made

in the shape of a helmet and is situated at the point where the handle and the blade meet. 15

The essential features of my design are the narrow pointed blade, the handle, and the helmet-shaped piece situated at the point where the handle and blade meet.

I claim—

The design for a letter opener as herein shown and described.

CHARLES H. BESLY.
